UNITED STATES PATENT OFFICE.

EMERSON M. HYATT, OF WARREN, PENNSYLVANIA, ASSIGNOR OF ONE-HALF TO
HENRY B. TAYLOR, OF WARREN, PENNSYLVANIA.

PROCESS FOR PRODUCING GASOLINE.

Application filed August 31, 1921. Serial No. 497,171.

To all whom it may concern:

Be it known that I, EMERSON M. HYATT, a citizen of the United States, residing at Warren, in the county of Warren and State 5 of Pennsylvania, have invented certain new and useful Improvements in Processes for Producing Gasoline, of which the following is a specification.

My invention relates to a process of cracking oils of high boiling points, such as fuel oil, kerosene, still bottoms, etc., for producing an oil of a low boiling point, such as gasoline.

The object of the invention is to provide 15 a simple and economical process for producing the maximum amount of gasoline, which may be obtained from fuel oil or the like, and at the same time produce a gasoline of a high grade.

Other objects and advantages of the invention will be apparent during the course 20 of the following description.

The drawing is a diagrammatic view of 25 apparatus which may be preferably employed in the practice of my process.

In the drawings, the numeral 10 designates a still receptacle or tank, which is preferably constructed of iron and adapted to withstand 150 pounds pressure to the square 30 inch. The numeral 11 designates a chlorine supply pipe, preferably discharging into the bottom of the still tank 10, and leading into a chlorine supply tank 12, which may be supported upon a suitable scale 13, if desired. The pipe 11 is provided adjacent to the chlorine tank 12 with a cut-off valve 14, and also has a check valve 15, opening in the direction of its arrow. The numeral 16 designates a fuel oil tank, having connection 35 with an outlet pipe 17, which leads into the still tank 10, as shown. The pipe 17 has a cut-off valve 18, as shown. A drain pipe 19 is connected with the bottom of the still 40 tank 10 and has a cut-off valve 20. The still tank 10 may be heated by any suitable means, such as by means of a burner 21, adapted to use oil or any other suitable fuel. An escape pipe 22 is connected with the top 45 of the tank 10, and has a cut-off valve 23 connected therein. An acid vapor outlet pipe 24 is connected in the escape pipe 22 and has a cut-off valve 25 connected therein. The vaporized hydrochloric acid to be referred to, passes through this pipe 24, and 50 is collected in a suitable receptacle. Out-

wardly of the cut-off valve 23 an escape valve 26 is connected in the escape pipe 22, and has a pipe 27 connected therewith. The escape valve 26 may be set to open at any selected pressure, to permit the gases to pass 60 from pipe 22 into pipe 27, and I have found it advantageous to have the escape valve 26 adapted to open at pressures varying from 75 to 150 lbs. to the square inch. The pipe 27 leads to the coil 28 of a condenser, of any 65 well known or preferred type, and this condenser discharges into a closed collecting tank 29. This tank has an outlet pipe 30, equipped with a cut-off valve 31. The pipe 30 discharges into a still 32, of any 70 well known or preferred construction. This still is heated by any well known means, and the products of distillation pass through a pipe 33, as is well known.

In the practice of my process, I may introduce 75 a suitable amount of the fuel oil into the still tank 10, by opening the valve 18, subsequently to which this valve is closed. I may introduce for instance ten barrels containing fifty gallons. Of course the 80 volume of oil treated will depend entirely upon the capacity of the apparatus employed. I next open the chlorine valve 14, and the liquid chlorine in the tank 12 will vaporize and pass through to pipe 11, into 85 the oil contained within the tank 10, the oil preferably filling about two-thirds of the tank. I preferably employ from 1 to 10 pounds of the liquid chlorine for each barrel of oil of fifty gallons, and I would therefore 90 introduce from ten to one hundred pounds of the liquid chlorine into the tank 10, in accordance with the present illustration. Of course this amount of liquid chlorine may be widely varied, as may be found 95 advantageous. The tank 12 being supported upon a scale 12, the number of pounds of liquid chlorine employed may be readily ascertained. The valve 14 is now closed and the tank 10 is heated by the operation of the 100 burner 21 or other suitable means. The contents of the tank 10 is now heated preferably from about 200° F. to 350° F., so that the contents will be subjected to a pressure within the tank from 75 to 150 pounds per 105 square inch. The oil and chlorine mixture are preferably subjected to this heat and pressure for from 12 to 48 hours while this time may be varied considerably, as may be found advantageous.

At the end of this period of from 12 to 48 hours the valve 25 is opened, and the excess hydrochloric acid vapor, which is formed during the treatment of the oil, as above explained, is released and discharges from the pipe 24 to an absorption tower, preferably containing moist scrap iron or other absorbent. After this excess hydrochloric acid vapor has been thus removed, the valve 25 is closed, and the still heated to from 650° F. to 750° F., which is the ordinary cracking temperature and the pressure within the still will be raised to from seventy five to one hundred and fifty pounds per square inch. This heat and pressure is maintained throughout the distillation period. The valve 23 is now opened and the escape valve 26 adjusted to open at from seventy five to one hundred and fifty pounds, as may be desired. The valve is preferably so adjusted that the products of distillation are allowed to escape through the pipe 27 at the rate of from 5% to 10% per hour, with respect to the entire volume of the oil being treated. The cracking or decomposition of the fuel oil takes place in the vaporized condition, in the upper portion of the still tank 10, and these vapors are cracked and produce hydrochloric acid, gasoline, kerosene, and heavy oil. This vaporized mixture passing the relief valve 26, as above explained, will pass into the condenser coil 28, and hence into the collecting tank 29, in the liquid form. By opening the valve 31 this liquid mixture will pass to still 32. In this still the liquid mixture is subjected to the action of heat, in the well known manner, for fractional distillation. The gasoline having an acid reaction first passes through the pipe 33, and the other products are brought over in their order. The gasoline may be treated in the usual manner, such as being agitated with a caustic soda solution, and subsequently washed in water. I have found that my process will produce from 60% to 70% of gasoline from the fuel oil treated, such gasoline having a gravity of 60 Bé.

It is to be understood that the form of my invention herewith shown and described is to be taken as a preferred example of the same, and that various changes may be resorted to in the order of the steps of the process, and changes made in the application of heat and pressure, and that chemical equivalents may be employed, without departing from the spirit of my invention, or the scope of the subjoined claims.

Having thus described my invention, I claim:

1. The herein described process of producing gasoline from fuel oil, which consists in first subjecting the fuel oil to the action of chlorine gas in the presence of heat beneath the cracking temperature and pres-

sure for a suitable period, withdrawing the excess hydrochloric acid gas produced, then subjecting the mass to a further treatment of a cracking temperature and pressure for a suitable period for effecting the decomposition of the fuel oil, withdrawing the vapors from the presence of the mass being treated, causing the vapors to be condensed, and subjecting the condensed vapors to fractional distillation for separating out the gasoline obtained.

2. The herein described process of producing gasoline from oils having high boiling points, which consists in first subjecting such oils to the action of chlorine gas in the presence of heat beneath the cracking temperature and pressure for a suitable period, withdrawing the excess hydrochloric acid gas produced, then subjecting the mass to a further treatment of a cracking temperature and pressure for a suitable period for effecting the decomposition of said oils, withdrawing the vapors from the presence of the mass being treated, causing the vapors to be condensed, and subjecting the condensed vapors to fractional distillation for separating out the gasoline obtained.

3. The herein described process of producing gasoline from fuel oil, which consists in first subjecting the fuel oil to the action of chlorine gas without the presence of a catalytic agent in the presence of heat beneath the usual cracking temperature and pressure for a suitable period, withdrawing the excess hydrochloric acid produced, then subjecting the mass thus treated to the action of a cracking temperature in the presence of pressure for a suitable period for effecting the decomposition of the oil, withdrawing the vapors from the presence of the mass, and recovering the gasoline constituents from said vapors.

4. The herein described process of producing gasoline from oils having high boiling points, which consists in subjecting approximately 50 gallons of oils of high boiling points to the action of chlorine gas derived from 1 to 10 pounds of liquid chlorine, and heating the mass while subjected to the action of the vaporized chlorine, withdrawing the excess hydrochloric acid produced, subjecting the mass to a further treatment of heat and pressure, withdrawing the vapors from the presence of the mass being treated, causing the vapors to be condensed, and subjecting the condensed vapors to the action of fractional distillation for separating out the gasoline obtained.

5. The herein described process of producing gasoline from oils having high boiling points, which consists in subjecting approximately fifty gallons of such oils to the action of chlorine gas derived from 1 to 10 pounds of liquid chlorine, in the presence of heat and pressure, said heat being from

200° F. to 350° F., and the pressure from 75 to 150 pounds per square inch, such operation continuing for from twelve to forty-eight hours, withdrawing the excess hydrochloric acid gas produced, then heating the

mass to from 650° F. to 750° F., and maintaining a pressure of from 75 to 150 pounds, per square inch, and allowing the gases pro-

duced to escape while maintaining this pressure, condensing the gases thus escaping, 10 and subjecting the condensed gases to fractional distillation to separate out the gasoline obtained.

In testimony whereof I affix my signature.

EMERSON M. HYATT.
